WILLARD V. HERSHY, OF FREMONT, OHIO, ASSIGNOR TO THE SCHAAF & GOOD COMPANY, OF FREMONT, OHIO, A CORPORATION OF OHIO

METHOD AND MEANS FOR FASTENING NONMETALLIC ELEMENTS TO METAL

Application filed March 21, 1929. Serial No. 348,914.

This invention relates to the fastening of non-metallic elements to metal, with special reference to the manufacture of manicuring and toilet articles, or other similar articles having a metallic body portion with a covering 5 of celluloid or analogous material.

In the manufacture of nail files, for example, it has long been customary to form the file portion with an integral extension having flat faces to which thin scales of celluloid or 10 equivalent material are secured to constitute a handle.

Scales have been produced for this purpose in excellent imitation of mother of pearl and 15 in other very attractive styles. It has been impossible, however, to produce a cement which will insure a satisfactory bond between the scales and the metal, and rivets or similar securing means are not only more costly, 20 but are unsatisfactory in appearance.

In an endeavor to overcome these objections it has heretofore been proposed to form holes through the metallic portion of the handle and to fill these holes with cement or 25 with solid inserts of the same material as the scales, so that in the region of such holes, the cement will directly unite two surfaces which are both of celluloid or equivalent material, and will thereby constitute a stronger bond 30 than where the metal is interposed between them.

Such methods have also proved unsatisfactory for various reasons. They not only add considerably to the cost of manufacture, but 35 the drying or setting of the cement in the region of the holes sets up greater stress in those regions than elsewhere not only resulting in unsightly depressions in the scale material, which is quite soft, but causes a 40 tendency for the scales to peel or curl up at the edges where they are less securely held.

With the above conditions in mind, the present invention has been perfected with the object of avoiding the objections and difficulties above described, and providing an article in which the scales are held most securely at points around the edges thereof. Another advantage resulting from my invention, which is of the utmost importance in 45 articles of this kind, is the fact that the cost of manufacture is materially less than where the solid inserts are used, as well as producing far better results.

My invention will be more specifically described in connection with the accompanying drawings, illustrating one of the articles which may be made in accordance therewith. 55

In the drawings:

Figure 1 is a face view of a nail file constructed in accordance with the invention, a portion of the handle being broken away. 60

Figure 2 is an edge view of the same.

Figure 3 is a perspective view illustrating portions of the handle before they are cemented together. 65

Figure 4 is a perspective view of a portion of the handle completed. 70

In the article illustrated herein, the file is formed with an integral extension 6, which constitutes a handle portion and which is usually recessed as at 7 to form a finger hold. The metallic handle portion 6 has flat faces which are adapted to be covered with thin scales 8 of celluloid or similar material. These scales may be made to imitate mother of pearl or in various other attractive colors and designs. 75

The chief problem which arises in connection with the manufacture of articles of this nature is due to the fact that no cement has been produced which will establish a satisfactory bond between the celluloid and the metal. Without some other means for securing the scales, the slightest force will sometimes cause the scales to peel off. The formation of holes through the body portion 6 and the bonding of the scales 8 through such holes, either by rivets, cement, or by the use of solid inserts of celluloid cemented to the inner faces of the scales, has proven unsatisfactory for various reasons above explained. 80

In order to overcome these difficulties and to satisfactorily secure the scales to the body portion 6, particularly along the edges thereof, excellent results have been obtained at a minimum cost by providing a plurality of notches, as indicated at 9, in the edges of the metallic portion 6 and filling these notches with cement to bond the scales directly to each other. The securing of the scales to the 85

articles of this kind, is the fact that the cost 90

100

metal may be aided by applying a thin coating of cement between the scales and the metal, but the most essential part of the process is the provision of the direct bonds 8 along the edges of the handle where the notches are formed. It is preferred to form these notches at equal distances along the edges of the metal, and the best results are obtained if the notches on one side are staggered with relation to the notches on the other side.

In manufacturing articles according to this process, the handle is preferably made slightly oversize and the edges ground off after the 15 cementing operation is completed. The particular shape of the notches is not important, but they should be deep enough so that a substantial portion thereof will be left after the edges are ground down.

20 During the process as invented by me, as the cement dries, if there is any contraction thereof, it is in the plane of the metal rather than transversely thereto, so that no unsightly depressions are formed in the celluloid, and any irregularities left in the edge are subsequently taken off by the final grinding thereof. Moreover, if the edges should be drawn inwardly a trifle toward each other by the cement, it will not be as objectionable 25 as in the case where the contraction is near the center.

While I have illustrated the invention only in connection with a nail file, it will be readily understood that the same is capable of use in 35 the manufacture of many other articles which involve the formation of a bond between metallic and non-metallic materials. It is also apparent that various features of the invention may be considerably modified without departing from the scope of the claims 40 hereunto appended.

What I claim is:

1. A device of the character described comprising a strip of metal formed with notches 45 in its edges, scales of non-metallic material cemented to opposite faces of said strip with cement substantially filling said notches and directly connecting the edges of the respective scales to each other.

50 2. A device of the character described comprising a strip of bare metal with an integral extension constituting a handle portion, said handle portion being formed with notches in its edges, and scales of non-metallic material 55 cemented to opposite faces of said handle portion, with cement substantially filling said notches and connecting the edges of the respective scales to each other.

60 3. A device of the character described comprising a strip of bare metal with an integral extension constituting a handle portion, said handle portion being formed with notches in its edges, the notches on each side being 65 spaced at substantially equal distances from each other and staggered with relation to the

notches on the opposite side, scales of non-metallic material cemented to opposite faces of said handle portion with cement substantially filling said notches and connecting the edges of the respective scales directly to each other.

In testimony whereof I have hereunto signed my name to this specification.

WILLARD V. HERSEY.
